UNITED STATES PATENT OFFICE.

JOHN A. LAMONT, OF GRANITE CITY, ILLINOIS, ASSIGNOR TO AMERICAN STEEL
FOUNDRIES, OF NEW YORK, N. Y., A CORPORATION OF NEW JERSEY.

SPRING-PLANK-LOCKING DEVICE.

Specification of Letters Patent. Patented Apr. 13, 1915.

1,135,591.

Application filed January 2, 1915. Serial No. 30.

To all whom it may concern:

Be it known that I, JOHN A. LAMONT, a citizen of the United States, and resident of Granite City, in the county of Madison 5 and State of Illinois, have invented certain new and useful Improvements in Spring-Plank-Locking Devices, of which the following is a specification.

My invention relates to car trucks and has 10 particular reference to a novel spring plank locking device for use in connection therewith.

It is essential in the operation of car trucks that the side frames shall be tied together intermediate their ends, this usually 15 being accomplished by the use of a spring plank or similar connecting device. In the use of cast side frames it is desirable that means shall be provided for readily dispensing 20 gaging the tying member therefrom and many devices have been proposed with that end in view. However, all of these devices have certain objections which are sought to be overcome in the present structure.

25 The tying member or spring plank need not be of great size or weight. In fact a comparatively thin section of metal may be utilized and preferably this member should be of considerable width in order to secure 30 certain advantages which are well known to those skilled in the art. In the use of a thin section for the spring plank it is somewhat difficult to provide any integral attaching element by means of which the plank or 35 plate may be secured to the side frames. Furthermore, it is essential that the springs should rest upon a block or filler in order to provide a secure seat therefor. Such a device is combined with the spring plank 40 locking element in the present structure.

The invention will be more readily understood by reference to the accompanying drawings, wherein,

Figure 1 is a fragmentary side elevation 45 of a side frame with my novel improvements applied thereto; Fig. 2 is a plan view partly in section showing the same, and Fig. 3 is a section on the line 3-3 of Fig. 1.

Referring more particularly to the drawings it will be seen that the side frame 10, 50 is provided with a bolster opening 11, and with a seat or shelf 12, on which a spring plank or plate 13, may rest. This spring

plank may or may not be provided with the flanges 14. At each end the plank 13 is 55 provided with four apertures 15, registering with similar apertures 16, through the seat 12. As a locking means I provide a block 17, having bosses 18, projecting from one face thereof, these bosses being adapted to enter the registering openings in the spring plank and seat. On the upper surface of the block 17, are small recesses 19, with which lugs, carried by the spring retainer, may cooperate.

65 It will be seen that by the use of the construction shown the spring plank is securely held in place without the use of rivets or bolts and that a comparatively light spring plank may be employed, the locking member 70 for the parts providing also a block on which the springs may rest.

The construction is capable of considerable modification and such modifications as are within the scope of my claims I consider 75 within the spirit of my invention.

I claim:

1. In a car truck, a side frame having an apertured seat, a spring plank, and a block 80 provided with bosses, said block resting upon said plank and said bosses serving to lock said spring plank and side frame together.

2. In a car truck, the combination of a side frame having an apertured seat, a 85 spring plank having apertures registering with those in said seat, and a block having bosses registering with the apertures in said plank and seat and adapted to removably lock the parts together.

3. In a car truck, the combination of a side frame member having an apertured seat, a plate extending between adjacent side frames, said plate being provided with apertures in its ends registering with the apertures in said side frame member, a spring-supporting block, and lugs on said block, 95 said lugs being adapted to enter apertures in said plate and side frame member and lock said parts together.

Signed at Granite City, Illinois, this 29 day of December, 1914.

JOHN A. LAMONT.
